UNITED STATES PATENT OFFICE.

ANTHONY FRONEK, OF CLEVELAND, OHIO, ASSIGNOR TO THE McMYLER INTERSTATE COMPANY, OF BEDFORD, OHIO, A CORPORATION OF OHIO.

BRAKE MECHANISM FOR LOCOMOTIVE-CRANES AND THE LIKE.

1,193,006.

Specification of Letters Patent.

Patented Aug. 1, 1916.

Application filed June 8, 1914. Serial No. 843,604.

To all whom it may concern:

Be it known that I, ANTHONY FRONEK, a citizen of the United States, residing at Cleveland, in the county of Cuyahoga and 5 State of Ohio, have invented a certain new and useful Improvement in Brake Mechanism for Locomotive-Cranes and the like, of which the following is a full, clear, and exact description.

10 This invention relates to brake mechanism for locomotive cranes and other apparatus having a turntable upon which the main parts of the operating mechanism are mounted.

15 The object of the invention is to provide a mechanical brake which can be conveniently controlled by the operator on the turntable, and which has its parts so arranged and mounted that when the turntable is turned the crane or other apparatus as a whole will not be moved along the track as has been the case heretofore with attempts to apply a brake to some point of the driving mechanism near the turntable and 20 with the brake band anchored or carried by the turntable.

25 My invention may be briefly summarized as consisting in certain novel details of construction and combinations and arrangements of parts which will be described in the specification and set forth in the appended claims.

30 In the accompanying sheets of drawings wherein I have shown the preferred embodiment of my invention, Figure 1 is a side view of the locomotive crane equipped with my invention, some parts being omitted and other parts being broken away. Fig. 2 is a 35 plan view of a portion of the turntable. Fig. 3 is a detached view of the brake operating mechanism. Fig. 4 is a vertical sectional view through the crane substantially along line 4—4 of Fig. 1. Fig. 5 is an enlarged view showing the construction around the 40 pivotal axis of the turntable and a portion of the gearing and vertical driving spindle by which the crane is propelled along the track, and Fig. 6 is a sectional view substantially along the line 6—6 of Fig. 5 looking upward.

45 The crane which is adapted to travel along

the track 10 includes wheeled trucks 11 and a main frame or body 12, which at its top is provided with a circular track 13 on which is a group of rollers or wheels 14 supporting a. 55 turntable 15, which is adapted to be turned or rotated about a vertical axis. Both the body 12 and the turntable 15 may be of any suitable construction, these parts being preferably formed chiefly of structural mate- 60 rial, as shown particularly in Fig. 4.

65 The turntable carries practically all of the operating mechanism, which includes a boom 16, a boiler 17, a cable drum 18 and engines 19, which through suitable transmitting devices are adapted to propel the crane as a whole along the track 10, to rotate the turntable, to shift the boom and raise and lower the load. As my invention does not 70 reside in these parts, the operating mechanism is shown in rather conventional manner, and practically all the details not necessary to an understanding of my invention have been omitted.

75 The locomotive crane is adapted to be propelled along the track through the medium of a vertical driving shaft 20, and it is about the axis of this shaft that the turntable 15 is adapted to be rotated. The driving shaft 20 is provided at its upper end with a bevel 80 gear 21 adapted to be driven by either one of two bevel gears 22 which are mounted on and adapted to be clutched to a shaft 23 rotated by the engines. The shaft 20 is provided at its lower end with a bevel gear 24. 85 which meshes with a bevel gear 25 mounted on a countershaft 26 suitably geared to one of the truck axles.

90 For the purpose of properly supporting the vertical driving shaft 20, and also for effectively centering the turntable the shaft 20 is journaled in a relatively fixed sleeve, quill, or bushing 27 secured near its lower end to an annular casting 28 carried by the frame or body 12. A second annular casting 29 is secured to the turntable and has a bearing on the sleeve 27 and on the casting 28.

95 To brake the crane so that the same can be held stationary on the track 10, it is not 100 feasible to provide brakes which are applied directly to the track wheels, in view of the

fact that the brake operating mechanism must be on a turntable and within convenient reach of the operator at his station. It has been proposed to apply the brake to 5 some part of the driving mechanism, but the best efforts along this line have required that the brake band be carried by or anchored to the turntable, but this has a serious and in many instances a fatal disad- 10 vantage that when the turntable is turned the brake band is turned and when the brake band is in braking engagement with the brake drum rotation of the band carries with it the band engaged part of the driving 15 mechanism, and this moves the apparatus as a whole forwardly or rearwardly along the track depending upon the direction in which the turntable is turned.

In the attainment of the objects of this 20 invention, I utilize a part of the driving bevel gear 21 at the top of the driving spindle 20 as a braking surface to be engaged by a brake band, and provide means for anchoring or supporting the band at 25 the upper end of the sleeve 27 through which the shaft 20 extends. In the accomplishment of this I provide a special gear 21 having a depending annular flange 30 to the outer surface of which a brake band 31^a 30 is adapted to be applied. In order to support this band on the non-rotating part of the apparatus, I provide at the top of the sleeve 27 an annular laterally projecting flange or head 31 to which the band is 35 anchored. The free ends of the bands are connected to pins supported by arms 32^a of bell cranks 32 mounted on pins 33 supported by and depending from the horizontal head 31. Midway between its ends or diamet- 40 rically opposite the bell cranks the band is supported by a projection 34 on the head 31.

Although the particular details of the clutch used are immaterial to my invention in its broad aspects, nevertheless I prefer to 45 employ the brake mechanism shown in this application in detail. In this brake, the mechanism for causing the band to be applied to flange 30 or to be released therefrom includes a shifter sleeve 35, which surrounds 50 and is adapted to be moved vertically along the upper portion of the sleeve 27. The mechanism for shifting this sleeve 35 will be explained presently. The sleeve 35 is engaged by the arms of the yoke 36 mounted 55 upon a pin 37 supported in lugs 38 depending from the head 31. (See particularly Fig. 6). Pivotaly connected between a pair of ears 39 projecting from the sleeve of the yoke surrounding the pin 37 is an arm in 60 the form of a bolt 40, which projects outwardly from the pin 37 and carries a trunnion block 41 connected at a central point to a rock arm 42, the free ends of which are connected by rods 43 to the outwardly 65 extending arms 32^b of the bell cranks 32,

The rock arm 42, which is adapted to be moved outwardly and inwardly by the end-wise movement of the bolt 40, and also is adapted to rock on the trunnion block 41 is composed of two plates, an upper plate and 70 a lower plate between which the central trunnion 41 is mounted. The rear ends of the lugs 38 project between the plates of this rock arm so as to guide the same.

It will be observed that the upward movement of the shifter sleeve 35 elevates the arms of the yoke 36, and tends to move the rock arm 42 inward toward the shaft 20, so as to rock the bell cranks to cause the brake to be contracted or to be applied, and the lowering of the shifter sleeve 35 tends to move the rock arm 42 outward so as to rock the bell cranks to release the brake. As a matter of fact, the brake is applied or released by a rocking of the rock arm about one end 85 rather than a bodily movement inward or outward. The movement of the arms 32^b of the bell cranks inward is limited by stop lugs 44 which are adapted to be engaged by pins 44^a carried by the bell crank arms 32^b 90 for a purpose to be described.

The brake shifting mechanism includes certain parts which are carried by and turn with the turntable, said parts including a foot pedal 45, which will be at the operator's 95 station. This foot pedal is mounted on a shaft connected by a link 46 to an arm 47 secured to a shaft 48 supported by the turn table or parts carried thereby, including the casting 29. (See Figs. 3 and 5). The inner 100 end of this shaft 48 is provided with a pair of shifter arms 49 loosely connected to pins projecting from opposite sides of a shifter ring 50, which is mounted in a groove at the lower end of the vertically moving shifter 105 sleeve 35. This ring is loosely mounted in the groove of the sleeve 35, so that the ring may turn with the turn-table and the brake operating mechanism including the shaft 48 and arms 49.

It will be observed that the principal part of the brake operating mechanism is carried by the turntable, but when the turntable is turned regardless of whether the brake is on or off the brake band will not be turned, 115 inasmuch as it is anchored to the non-rotating part of the apparatus.

This brake construction permits the brake to be applied without requiring the expenditure of a great deal of power or energy on 120 the part of the operator and this is true regardless of the direction in which the brake surface or flange 30 may be rotating at the time when the brake is applied, for regardless of the fact that neither end of the brake 125 band is permanently anchored or fastened, the power utilized in applying the brake will be applied chiefly, if not entirely, to that end of the band which when shifted will draw the band in the direction that the 130

flange 30 is being rotated. For example, when the brake is being applied by depressing the foot pedal 45 and elevating the shifter sleeves 35, engagement between the 5 brake band and the rotating flange 30 will tend to drag the band around with the latter and will rock one of the bell cranks 32 so as to swing its arm 32^b inward until the pin 44^a carried by said arm engages the 10 corresponding stop lug 44. As soon as the pin 44^a engages the stop lug 44, thus limiting the inward rocking movement of the one bell crank and anchoring one end of the band, one end of the rock arm 42 thus becomes 15 fixed and the rock arm is turned or rocked by the brake operating mechanism about said fixed end, causing the other bell crank to be rocked so as to draw the band in the direction that the flange 30 is rotating 20 until complete engagement takes place and the brake is fully applied.

Having thus described my invention, I claim:

1. In a machine of the character described, a frame or body having wheels adapted to travel along a track, a turntable mounted on said frame or body for movement about a vertical axis, driving mechanism for propelling the machine along the 25 track, a brake, including a brake member adapted to coöperate with a part of the driving mechanism and supported independently of the turntable, and means for operating the brake comprising a brake operating member supported by the turntable and mechanically connected to said first named brake member.

2. In a machine of the character described, a frame or body having track 40 wheels adapted to travel along a track, a turntable mounted on said frame or body, mechanism for propelling the machine including a source of power carried by the turntable, a brake comprising a brake member adapted to coöperate with a part of the propelling mechanism and supported independently of the turntable, means for operating the brake, comprising a brake controlling member carried by the turntable and 45 mechanically connected to said brake member.

3. In a machine of the character described, a frame or body having wheels adapted to travel along a track, a turntable 50 mounted on said frame or body for movement about a vertical axis, motive means mounted on said turntable for propelling the car, driving mechanism including a vertical shaft for connecting said motive means with track wheels of the machine, and a 55 brake arranged concentrically with respect to said shaft and including a brake member supported independently of the turntable, and mechanism for operating the brake.

4. In a machine of the character de-

scribed, a frame or body having track wheels, a turntable mounted on said frame or body for movement about a vertical axis, propelling mechanism for said machine mounted on the turntable, and a vertical 70 driving shaft for transmitting power to the track wheels, a brake arranged adjacent to the turntable and comprising a rotary part concentric with respect to said shaft, and a band adapted to engage said part and supported independently of the turntable, and mechanism for operating the brake.

5. In a machine of the character described, a frame or body having track wheels, a turntable supported by said frame 80 or body for movement about a vertical axis, power mechanism on the turntable for propelling the machine along a track, a shaft connected to said power mechanism and to the track wheels, a sleeve surrounding the 85 shaft and supported by said frame or body, a brake for the machine comprising a part rotatable with said shaft and a brake band supported by said sleeve and means controllable from the turntable for shifting said 90 brake band.

6. In a machine of the character described, a frame or body having track wheels, a turntable supported by said frame or body for movement about a vertical axis, 95 power mechanism on the turntable for propelling the machine along a track, a shaft extending upwardly from the frame or body and connected to said power mechanism and to the track wheels, a sleeve surrounding the 100 shaft and supported by and extending upwardly above said frame or body, a brake for the machine comprising a cylindrical member carried by the shaft adjacent to the upper end thereof, and a brake band adapted to engage said cylindrical member and carried by the upper part of said sleeve, both parts of said brake being above the frame or body and adjacent to the turntable, and means for controlling the brake comprising 110 parts rotatable with the turntable.

7. In a machine of the character described, a frame having track wheels, a turntable supported by said frame for movement about a vertical axis, power mechanism on the turntable for propelling the machine along a track, power transmitting mechanism extending from the turntable to the track wheels of said frame, a brake comprising a cylindrical member rotatable with 120 and connected to the power transmitting mechanism and a brake band adapted to engage said member and supported adjacent the turntable but independently thereof, and mechanism for operating said band, 125 said mechanism being supported partly by the turntable so as to rotate therewith, and partly by the frame.

8. In a machine of the character described, a frame or body and a turntable 130

supported by the frame or body and adapted to be turned about a vertical axis, a brake for the machine comprising a brake band anchored on a part which is stationary relative to the turntable, and a brake operating member supported by the turntable and connected to the brake band.

In testimony whereof, I hereunto affix my signature in the presence of two witnesses.

ANTHONY FRONEK
